UNITED STATES PATENT OFFICE.

WILLIAM W. LASKER, OF BROOKLYN, NEW YORK, ASSIGNOR, BY MESNE ASSIGNMENTS, TO REMINGTON RAND INC., OF NEW YORK, N. Y., A CORPORATION OF DELAWARE.

CARRIAGE RETURN AND NORMALIZING MECHANISM FOR CARD-PERFORATING MACHINES.

Application filed April 28, 1927. Serial No. 187,194.

This invention relates to carriage return mechanism for card punching or perforating machines and the principal object of the invention is to produce a device of this na-

ture in which the carriage may be returned from any position other than its normal position to normal position by magnetic means.

Another object of the invention is to produce a device of this nature in which the magnetic carriage return cannot be energized if the carriage is standing in its normal or "home" position.

Another object of the invention is to produce a device of this nature in which the mechanism may be adjusted for determining any desired position of the carriage as the "home" or normal position, and for effecting a positive de-energizing of the magnetic means when the carriage return key has been depressed and the carriage has been completely returned to "home" position, regardless of whether the carriage return key is held down during the entire return of the carriage or is released during the return of the carriage.

With these and other objects in view the invention resides in certain novel construction and combination and arrangement of parts which will be hereinafter fully described and specifically claimed and which are shown in the accompanying drawings in which:

Fig. 1 is a fragmentary front elevation of a card perforating or punching machine provided with my improved magnetic carriage return, parts being broken away for the sake of clearness.

Fig. 2 is a fragmentary vertical sectional view of the machine shown in Fig. 1.

Fig. 3 is a detail view showing the carriage being returned by the carriage return mechanism.

Fig. 4 is a top plan view of the mechanism shown in Fig. 3.

Fig. 5 is a view similar to Fig. 3 but showing the carriage returned to its normal or "home" position.

Fig. 6 is a fragmentary detail view indicating the relay and mechanism operated thereby.

Fig. 7 is a top plan view of the mechanism shown in Fig. 6.

Fig. 8 is a diagrammatic view indicating the electrical circuits.

Like characters of reference refer to like parts in all figures.

Referring to the drawings in detail 20 represents the general framework of the machine, the machine shown in the drawings and to which my invention has been attached being a punching or perforating machine in common use and known on the market as the Powers punch, such for example as that illustrated in Letters Patent of the United States, No. 1,643,779 granted to W. W. Lasker Sept. 27, 1927. 21 represents a carriage provided with wheels 22 which ride upon rails 23 so that the carriage is movable transversely of the machine, as shown in Fig. 1. Movement of the carriage toward the right is effected by a spring drum such as shown in the patent to Lasker referred to but not shown herein, or suitable means, such movement being controlled by an escapement wheel 24 and escapement pawls 25 and 26.

As shown in Fig. 2, the carriage 21 carries a plurality of setting members 27 which are arranged in a row from front to rear of the machine, said setting members corresponding to and being controlled by keys or finger pieces (not shown) each operable to cause depression of its respective setting member 27. The row of setting members 27 is movable over a field of set-bars 28 there being a plurality of rows of such bars and each row comprising a respective bar 28 for each of the setting members 27. The movement of the carriage brings setting members 27 over the set-bars 28 of one column after another of the set-bars 28. Upon the depression of one of the setting members 27 a respective set-bar 28 over which it is at that time located, is depressed, and is held in depressed position by a spring pressed latch bar 29, which engages with a shoulder 30 on the depressed bar 28. In moving down, this depressed bar 28 will have depressed a set-bar spring-pin 31. There is one pin 31 for each of the bars 28, and each pin 31 is urged upwardly by a respective spring 32 which effects the return to normal position of the respective members 31 and 28 when free from the latch bar 29.

100

Each of the latch bars 29 has its right-hand end, Fig. 2, arranged adjacent to a respective pivoted releasing pawl 37, and formed with an oblique face 38. A plurality of punches are indicated at 33 there being one punch located under each pin 31. All of the punches are mounted in a stripper bar 34, and have their lower ends extending into a movable frame 35 comprising a die and guide plates and formed with a card throat or passage 36. The frame 35 is adapted to be vertically reciprocated by means (not shown), and when a card is in the passage 36, the card is moved with the frame and encounters all of the punches 33, lifting them with it. If a pin 31 is in a depressed position, it will stop the upward movement of its respective punch 33 and said punch will be forced through the card thereby 20 by perforating the same. All of this mechanism is old and well known in the art and in machines on the market and in common use.

Pivottally mounted on the escapement 25 wheel shaft, Fig. 1, is a rock member 39 provided with an arm 40 connected by a link 41 to a rock lever 42 which rock lever is pivottally mounted on the carriage frame and carries at its free end a beveled roller 43. When rock member 39 is rocked from the position shown in Fig. 1 to the position shown in Figs. 3 and 5, the roller 43 is moved downwardly so as to contact face 38 of the pawls 37; and if the carriage is then 35 returned toward the left the roller will cause all of the pawls 37 which it contacts, to move their respective latch bars 29 so as to effect releasing of any set bars 28 which may have been locked in set position. This mechanism is also old and well known in the art.

Secured to the main framework of the machine is a rod 44, Fig. 3, which carries a slidable block 45 formed with a cam element 46 and a carriage return tooth 47. Secured 45 to the bottom of the block 45 is a tape 48 which is connected to a shock absorbing spring 49, said spring 49 being secured to a spring drum 50. This spring drum tends constantly to shift the block 45 toward the right-hand side of the machine as shown in Figs. 1, 3, and 5. A second tape, indicated in Fig. 1 at 51, is secured to the bottom of the block 45 and runs to the left passing over an idler roller 52 downwardly therefrom, having its lower end secured to a drum shaped magnet 53. The magnet 53 is freely mounted on a sleeve 54 secured to and rotatable by a constantly running shaft 55 of the machine. The sleeve 54 is provided 55 with a disk or flange 56 adjacent to the magnet 53.

It will now be seen that if the magnet 53 is energized it will grip the flange 56 and will be turned thereby in the direction indicated in Fig. 1, whereupon the tape or

strip 51 will be drawn so as to shift the block 45 to the left in Fig. 1. During the movement of the block 45, the cam 46, Fig. 3, engages a roller 57 mounted on the rock member 39 and lifts said roller 57 thereby 70 operating link 41 and roller 42 so as to render lever 43 effective for wiping out during the carriage return, whatever may have been set up in the machine. Tooth 47 on the block 45 now engages a roller or hub 75 58 mounted on the escapement shaft and draws the carriage toward the left.

We shall now consider the means for energizing the magnet 53 and the means for rendering the carriage return mechanism ineffective upon the carriage reaching normal or "home" position.

A bar 59 which guides block 45 in its movements, is formed with slots 60 through which pass pins 61 secured to a stationary part of the frame of the machine. This permits a limited amount of endwise movement of the bar 59 and said bar is normally held in its left-hand position against the tension of a spring 64 anchored to one of the pins 61 and secured at its other end to a pin 65 in the bar 59. Bar 59 is formed with rack teeth 66, and it is adapted to engage and hold the teeth of a spring pressed detent member 67 secured in a block 68 slidably mounted on the bar 59. The block 68 determines the "home" position of the carriage, that is, the farthest position to which the carriage may be returned. A finger piece 69 is provided for effecting disengagement of member 67 from the rack teeth 66 to enable the adjustment of the block 68 along the bar 59. The lower face of bar 59 is formed with a notch 70, Fig. 3, under its left-hand end to receive one arm 71 of 105 a bell-crank lever pivoted to a stationary part of the machine and having its other arm 72 provided with a contact or switch element 73, Figs. 6, 7, and 8. As indicated in Fig. 6 the end of the arm 72 is normally 110 held by a shoulder 74 formed on a rock lever 75; and in this position the contact element 73 is out of engagement with a contact element 76. At this time the bar 59 is held by the arm 71 to the left as indicated in 115 Fig. 5 with the spring 64 under tension. An auxiliary stop arm 77, Fig. 6, is formed with a shoulder 78 adapted at times to engage the arm 72 as will be presently described. A spring 79 holds the lever 75 and auxiliary stop arm 77 in contact with each other and a spring 80 constantly tends to draw the right-hand end of lever 75, Fig. 6, downwardly. The left-hand end of lever 75 as indicated in Fig. 6, is contacted by 120 the bottom of adjusting screw 81 which screw is mounted on the free end of an armature 82 adapted to be operated by a relay magnet 83.

Referring now to Fig. 8, it will be seen 125

that a wire 84 connects a lead line 85 with a contact 86. A carriage return key 87 is connected to a switch element 88 for operating the same so as to complete the circuit from contact 86 through the wire 89 to the relay magnet 83 and thence by a wire 90 to the return line 91. With the parts in the position shown in, Fig. 6, if the lever 75 is rocked counter-clockwise it will be seen that arm 72 will be freed from shoulder 74 and the lever 72-71 will be rocked by reason of the connection of arm 71 to the bar 59 and the action of spring 64 on said bar. When this happens the contact 73 will be moved into engagement with the contact 76 in Fig. 8 and a circuit will be closed from the lead 85 through a wire 92 to the magnet 53, thence through a wire 93 and contacts 76 and 73 to a wire 94 connected to the return lead 91.

The operation of the mechanism is as follows: When an operator has operated the keys of the punch machine so as to move the carriage from its "home" position toward the right, and thereafter depresses the carriage return key 87, the circuit is closed from 85, Fig. 8, through 84, 86, 88, 89, and the magnet 83, and wire 90 to the return lead 91 thereby energizing the relay magnet 83 which draws down its armature 82. The screw 81 effects counter-clockwise rocking of lever 75 so as to release arm 72 whereupon the lever 72-71 is moved with the bar 59 by the spring 64 to the extent allowed by the slots 60. The bar 59 carries with it the block 68. The lever 72-71 in moving brings the contact 73 into engagement with contact 76 thereby closing the circuit from 85 through 92, magnet 53 wire 93 contacts 76 and 73 and wire 94 to the return lead 91. This energizes magnet 53 which immediately grasps the flange 56 and is rotated thereby. This draws down on the tape 51 pulling the block 45, Fig. 1, toward the left against the tension of the spring in the drum 50. When the block reaches the position shown in Fig. 3, the cam 46 raises roller 57 thereby lowering the roller 43 to position to operate the release pawls 37; and the tooth 47 has engaged the roller or hub 58 on the carriage. As the operation continues the block 45 draws the carriage toward the left until the hub 58 engages the up-standing fingerpiece 69 of the block 68. The block 68 is thereby moved toward the left to the extent permitted by the slots 60, whereby the lever 71-72 is rocked so as to move contact 73 out of engagement with contact 76, Fig. 8, whereby the circuit through the magnet 53 is broken and the magnet immediately releases its grip on the flange 56. At the same time the auxiliary stop or shoulder 78 catches arm 72 and holds said arm and connecting parts against return movement. When the carriage return key is now released the armature 82 will rock clockwise moving the auxiliary stop 65 arm 77 downwardly until the arm 72 escapes the shoulder 78 and moves slightly so as to rest against shoulder 74. This slight movement is not sufficient to effect movement of the contact 73 into engagement with the contact 76. As soon as the magnet 53 is de-energized the spring drum 50 takes effect to draw the block 45 and its connected parts to the right to their normal position indicated in Fig. 1.

It will be seen that the relay circuit is entirely independent of the magnet circuit and merely effects the closing of the switch of the latter circuit, so that if the operator releases the carriage return key prior to the complete return of the carriage, the carriage will continue its movement and complete its return. It will also be seen that if the carriage return key is held in depressed position after the carriage has been fully returned, no further strain will be put on the parts, as the contact 73 is held against again engaging contact 76 by the engagement of the shoulder 78 with the end of the arm 72.

It will also be seen that when the carriage is returned, its escapement will lock it against the block 68 whereby the bar 59 will be locked against movement by spring 64. Consequently if the carriage-return key is operated with the carriage in "home" position, lever 75 merely moves idly, lever 71-72 being held against operation, and magnet 53 is not energized.

While I have described what I consider to be the most desirable embodiment of my invention, it is obvious that many changes in mechanism details can be made that depart from the spirit of my invention, and I therefore do not limit myself to the exact embodiment herein shown and described nor to anything less than to the whole of my invention as hereinbefore described and hereinafter pointed out in the claims.

What I claim as my invention is:

1. The combination with the carriage of a card punching machine, of a block normally out of the normal traverse of said carriage and formed with means for engagement with a portion of said carriage, electro-magnetic means for moving said block to effect return of said carriage to home position, and automatic means for returning said block to normal position after it has effected the return of said carriage.
2. The combination with the carriage of a card punching machine, of a block normally out of the normal traverse of said carriage and formed with means for engagement with a portion of said carriage, electro-magnetic means for moving said block to effect return of said carriage to home position, means for returning said block to home position after it has effected the return of

- said carriage, and means for preventing operation of said electro-magnetic means when said carriage is in home position.
3. The combination with the setting mechanism and carriage of a card punching machine, of means on said carriage operable to effect release of said setting mechanism, a block provided with means for engaging said carriage to effect return of the latter and also provided with means for operating the releasing means on said carriage, electro-magnetic means for operating said block to effect the return of said carriage to home position, and automatic means for effecting return of said block to normal position.
4. The combination with a carriage, of a constantly running shaft, an electro-magnet mounted on said shaft, an electrical circuit connected with said electro-magnet and including a switch, a second electrical circuit

for effecting operation of said switch, connections from said electro-magnet to said carriage for effecting return of said carriage to home position, and means operable by said carriage for operating the switch.

5. The combination with the carriage of a card punching machine, of a bar, mounted in juxtaposition to said carriage and adapted to have a limited movement imparted to it, a lever connected to said bar, an electric circuit including a switch operable by said lever, means for normally holding said lever in one position, electrical means for releasing said lever to effect operation of said switch, and means whereby said carriage may operate said bar, to effect movement of said lever for throwing said switch.

In testimony whereof I affix my signature.
WILLIAM W. LASKER.
